Patented May 11, 1920.

FIG. 1.

FIG. 2.

FIG. 3.

John M. McCray
Inventor

By *Geo. P. Kimmel*
Attorney

UNITED STATES PATENT OFFICE.

JOHN MOORE McCRAY, OF PUEBLO, COLORADO.

SHOE-HOLDER.

1,339,520.

Specification of Letters Patent.

Patented May 11, 1920.

Application filed June 10, 1918. Serial No. 239,152.

To all whom it may concern:

Be it known that I, JOHN MOORE McCRAY, a citizen of the United States, residing at Pueblo, in the county of Pueblo and State 5 of Colorado, have invented certain new and useful Improvements in Shoe-Holders, of which the following is a specification.

This invention relates to new and useful improvements in holding devices and the 10 primary object of the invention is to provide a simple device for detachably connecting a pair of shoes or the like so as to keep the shoes properly mated and prevent their misplacement when displayed for sale by 15 tailers. The device is adapted to be run through the upper adjacent eyelets of the shoes, and will securely connect the same but permit them to be easily released when necessary. This holder is also adapted for 20 use by manufacturers in keeping connected the correct pairs of shoes.

Another object of the invention is to provide a device of this character which is easily and simply constructed, inexpensive 25 to manufacture, and one which will be very efficient in operation.

With these and numerous other objects in view, my invention consists of the novel features of construction, combination and arrangement of parts which will be herein referred to and more particularly pointed out 30 in the specification and claims.

In the accompanying drawings:

Figure 1 is a perspective view of the device connecting the uppers of a pair of shoes,

Fig. 2 is a front elevation of the device, and

Fig. 3 is a top plan view of the same.

In describing my invention I shall refer 40 to the drawings in which similar reference characters designate corresponding parts throughout the several views.

The device is formed from a single piece of wire which is bent loop shaped intermediate its ends, the loop being designated by 45 the numeral 1, and having its ends disposed adjacent each other, with the ends of the wire projecting oppositely as shown at 2 and 3 but disposed in a single plane. The 50 loop 1 and the interengaged ends thereof form the clasping means for connecting the shoes as will be hereinafter more fully described.

The end 2 of the wire has the extremity

thereof bent laterally as shown at 4 at an 55 angle to the loop 1 and the outer end is bent downwardly substantially U-shaped as shown at 5, the extremity being disposed adjacent the offset portion 4. This formation will provide the holder with a handle, so 60 as to permit the same to be easily placed in position for use or removed from operative position.

In operation, to connect a pair of shoes, the shoes are held in the left hand, side by 65 side, and the outer end 3 of the holder is run through the eyelet of each shoe and then the holder is turned to the right until the sides of the handle thereof are at the top of the uppers of the shoes as clearly 70 shown in Fig. 1 of the drawings. This will securely connect the shoes and is quicker and better than tying the same with cord, such as is ordinarily done. This device is especially adapted for use to keep the shoes 75 in proper mates while being displayed on sales tables, and from being mixed in the shoe boxes by the clerks when showing the shoes to customers. It is more economical than strings, and is much more efficient for 80 the purpose as the strings become untied and consequently permit the shoes to be mislaid. The offset handle portion of the device permits the same to be easily removed 85 from operative position, as it is only necessary to grasp the handle, and turn the loop to the left to withdraw the holder from the shoes.

From the foregoing description taken in connection with the accompanying drawings, it is thought that a clear and comprehensive understanding of the construction, operation and advantages of my invention may be had, and while I have shown and described the device as embodying a specific 95 structure I desire that it be understood that such changes may be made in said structure as do not depart from the spirit and scope of the invention as claimed.

Having fully described my invention what 100 I claim as new and desire to secure by Letters Patent, is:

1. A holder of the character described formed from a single length of resilient wire bent to provide a handle extension and a 105 single coil at an angle thereto, the end of the wire remote from the handle extension being disposed tangentially to said coil, said

handle extension being disposed laterally at one side of the plane of the coil.

2. A holder of the character described formed from a single length of resilient wire bent to provide a handle extension and a single coil at an angle thereto, the end of the wire remote from the handle extension

being disposed tangentially to said coil, said handle extension being disposed laterally at one side of the plane of the coil, and of substantially looped form.

In testimony whereof, I affix my signature hereto.

JOHN MOORE McCRAY.
